UNITED STATES PATENT OFFICE.

CHARLES GLUCKMAN, OF NEW YORK, N. Y.

FAUCET ATTACHMENT.

1,163,081.

Specification of Letters Patent.

Patented Dec. 7, 1915.

Application filed February 20, 1915. Serial No. 9,722.

To all whom it may concern:

Be it known that I, CHARLES GLUCKMAN, a citizen of the United States, and a resident of the city of New York, in the county 5 of New York and State of New York, have invented certain new and useful Improvements in Faucet Attachments, of which the following is a specification.

This invention relates to improvements 10 in devices for combining the flow of fluids issuing from separate dispensing faucets into a single stream.

One of the objects of the invention is to provide a device that can be easily, and 15 quickly applied to a pair of ordinary twin faucets, disposed in the usual manner at the customary distance apart, without the use of any tools or appliances other than the fingers, and which can as readily be removed. 20

Another object is to arrange the device in such a manner as to be extended to accommodate various distances between faucet centers when in use, or which can be compactly folded when not in use. 25

A further object is to combine with the device a strainer, which assists in mixing the entering streams and also prevents the 30 passage of any material entrained in the fluids.

These and other objects, such as economical construction, symmetry of appearance and general adaptability, are attained by the novel construction and combination 35 of parts hereinafter described and shown in the accompanying drawing, forming part of this specification, and in which:—

Figure 1, is a perspective view of the device illustrating its application. Fig. 2, is 40 a side elevation and sectional view of the same, Fig. 3, is a top plan view of the device extended, and Fig. 4, is a side view of the same, shown in a folded position.

As indicated in the drawing, the device 45 consists of a mixing chamber 10, having the shape of a flattened funnel or hollow cone, provided with semi-circular side plate elements 11, joined at their ends by the concavely shaped upper end of the cone, which 50 at the bottom is formed with an annulus acting as a nozzle or spout 12. At the juncture of the spout with the cone an internal flange 14, is formed and engaged with it is a strainer 15, which may be made of metallic 55 gauze or other suitable material. At the center of the semi-circular sides 11, are

rivets 18, pivotally engaging with the lower ends of open trough-like conveyers 20, the same being made of thin material, and in such manner that the edges of one may be received into the other as they are closed together, both being between the plates forming the sides 11. Along the side walls of the conveyers 20, are outwardly impressed angular grooves 21, the same being arranged 60 in pairs, the depressions thus made being adapted to receive the stub ends of the trunnions 22, formed on opposite sides of the clamp rings, 24, thus permitting the rings to be attached to the spouts or nozzles of 65 the faucets irrespective of the distance apart of the same or the angularity that the conveyers may assume, and to be adjusted by engaging with any of the depressed receivers 21. In order to hold the rings 70 rigidly in engagement with the faucet spouts, thumb screws 25, are set in the rings, the operative heads extending toward the open sides of the conveyers, so as to be easily accessible in operating the same. 75 Thus it will be seen that an efficient device is provided that may be applied to or removed from any ordinary pair of faucets in a moment, such as are commonly used where hot and cold water are supplied to kitchen 80 sinks, fixed wash tubs, bath tubs, etc., and that by its use it is possible to deliver a single stream of water of the desired temperature by gaging the respective flow from 85 each faucet to suit requirements. 90

When not in use the device may be quickly removed and folded to occupy very little space wherever it may be convenient to dispose of it.

It will also be evident that the use of the 95 device is not restricted to water, but oils, syrups, and other fluids of varying density and specific gravity, or dry-powdered substance may be combined in any desired proportion and without waste or dripping, the 100 operation depending on gravity only.

As no valves, springs or packings are required there is nothing to get out of order and the device may be applied by any one 105 without previous experience.

The device being supported by the pivotally mounted clamp rings, it is self-adjusting, the discharge nozzle containing the strainer always hanging pendant centrally between the faucets, so that fluids flow by 110 gravity through it to the most convenient point for discharge and it will be apparent

that by reason of its design that it is completely self-draining.

Having thus described the invention and indicated the manner of its application and use, what I claim as new and seek to secure by Letters Patent, is:—

1. A flow combiner for twin faucets comprising a pair of conveyers disposed in converging inclined planes, means for pivotally attaching said conveyers to the faucets and a dispensing funnel receptive of said conveyers at a point of convergence thereof.
- 10 2. A flow combiner for twin faucets comprising a pair of conveyers each having a straight unbroken passage leading to the point of convergence, means for pivotally attaching said conveyers to the faucets, a dispensing funnel embracing said conveyers at their discharge ends and an attaching means therebetween, said attaching means permitting said conveyers to move pivotally with relation to each other and to said funnel.
- 15 3. A flow combiner for twin faucets comprising a pair of open conveyers pivotally connected at their lower ends, a pendant, self-adjusting discharge nozzle engaged therewith, and a faucet engaging means pivotally contained within the walls of said conveyers.
- 20 4. A flow combiner for twin faucets comprising a pair of trough-like, open conveyers, a flattened conical dispensing nozzle encompassing one end of each conveyer, means for pivotally uniting the sides of said nozzle with the walls of said conveyers, a spout-yoke pivotally mounted in the opposite end of each of said conveyers and a clamping means combined with said yokes.
- 25 5. A flow combiner for twin faucets comprising a pair of angularly disposed, open conveyers pivotally united at their converging ends, a dispensing nozzle pivotally engaged therewith and means for removably attaching said conveyers with the faucet spouts irrespective of the angle assumed by said conveyers.
- 30 6. A flow combiner for twin faucets comprising a pair of fluid conveyers, means for removably attaching said conveyers at different points along their lengths to the faucets and a self-adjusting discharge nozzle pivotally combined with said conveyers.
